U.S. Cl. D96—12

FIG.1

FIG.4

FIG. 1 is a perspective view of a combination display and coupon dispensing sign showing my new design;

FIG. 2 is a side elevational view of said sign;

FIG. 3 is a front elevational view thereof, the rear being the same as the front shown; and

FIG. 4 is a top plan view of said sign.

The characteristic feature of my design resides in the appearance of the coupon holding and dispensing portion thereof.

I claim:

The ornamental design for a combination display and coupon dispensing sign, substantially as shown and described.
